UNITED STATES PATENT OFFICE

2,037,770

CONTAINER

John M. Driver, San Francisco, Calif.

Application May 14, 1935, Serial No. 21,395

5 Claims. (Cl. 229—62)

This invention relates to new and useful improvements in containers generally, more particularly to a container or bag provided with a simple and inexpensive means whereby either or 5 both ends of said container or bag may be folded into a closed position.

An object of the invention is to provide a container whose walls are constructed of a flexible, foldable material such as paper, "cellophane", 10 glassine or the like, having either its open top or bottom ends adapted to be closed by folding the bag walls inwardly, one over the other, onto a preformed guide, which is thereafter foldable with the material of the bag to form a substantially rigid and relatively flat top or bottom.

A further object of the invention is to provide a container, each of the closed ends of which are composed of a plurality of inwardly folded flaps arranged in overlapping relation and folded 20 upon a separate foldable member within the bag, whereby one of said flaps, when unfolded, may be arranged in an upright position and carry printed indicia or advertising matter to assist in the purveyance of the commodity contained within 25 in the bag, and said one flap or both flaps, when unfolded, being provided with means through which a supporting member may be passed to hold the bag in a suspended position.

Other objects and advantages are to provide 30 a container that will be superior in point of simplicity, inexpensiveness of construction, positiveness of operation, and facility and convenience in use and general efficiency.

In this specification and the annexed drawing, the invention is illustrated in the form considered to be the best, but it is to be understood that the invention is not limited to such form, because it may be embodied in other forms; and 35 it is also to be understood that in and by the 40 claims following the description, it is desired to cover the invention in whatsoever form it may be embodied.

In the accompanying drawing:

Fig. 1 is a perspective view of the former member.

Fig. 2 is a perspective view of the upper open end of the bag with a portion thereof partially folded on the former member.

Fig. 3 is a perspective view of the upper end of a bag illustrating two of the flaps in upright position to receive the supporting member therethrough.

Fig. 4 is a perspective view of a bag closed in accordance with my invention illustrating the

method of applying a strip of adhesive tape for holding the same closed.

Fig. 5 is a perspective view of an end of a bag in partially folded position, and partly broken away to show the placement of my former member therein.

In the selected embodiment of the invention herein disclosed, I have provided a container or bag comprising a body portion 1 and a closed bottom. The container or bag may be formed 10 of any of the conventional and foldable materials out of which it is the usual practice to form bags or containers, and the bottom of the said bag may be closed either in any of the customary ways now in usage in the bag making industry, 15 or said bottom may be closed in the manner to be hereinafter set forth, and in accordance with the teachings of my invention.

The invention is particularly applicable to bags 20 of the general character shown in Fig. 3, which when filled with a suitable material, usually have their open tops closed by inwardly folding the bag top walls as illustrated in the various figures of the drawing. The bag top or the bag bottom is closed by inwardly folding the oppositely disposed wall portions 3 and 4, one over the other, whereby oppositely projecting flaps 5 and 6 are provided. A suitable adhesive or other securing 25 means may be applied to the engaging surface of the wall portions 3 and 4, whereby these portions are secured together when folded during the first step of the closing operation. It is the customary practice to close the bags by hand methods, and a great deal of skill is required in 30 folding bags which contain a commodity which 35 is of a slippery bulky nature, such, for instance, as coffee, beans, rice and the like.

In order to facilitate the closing of either end of the bag, or preferably the open top of the bag where the bottom end has previously been closed, 40 I place a member 7, preferably made of relatively stiff material, such as cardboard, within the bag and overlying the top of the contents thereof. The opposite ends 8 and 9 of the member 7 are 45 triangular in form and each is provided with a crease line along the base of the triangle, whereby each of the pointed ends of said member may be placed into an upright position and will conform to and be sealed within the oppositely projecting flaps 5 and 6 heretofore referred to.

The cardboard stiffener member which I place 50 on top of the contents of the bag, preliminarily to closing the end of the bag, functions as a guide or form which materially assists the operator in closing the end of the bag. With my stiffener 55

the operation of closing the end of the bag may be performed either by manual methods or the bag end may be closed through the instrumentality of automatic machinery.

5 With my member 7 in position, the first operation is to bring the oppositely disposed wall portions 3 and 4 into overlapping relation, thereby leaving the oppositely projecting flaps 5 and 6 upstanding around the triangular ends 8 and 9 of 10 the member 7. Thereafter the flaps 5 and 6, and the enclosed ends 8 and 9 are brought down into a flattened position on top of the overlapping portions 3 and 4, and secured thereto, either by means of adhesive or by means of a sticker pasted 15 over the tops of the folded-down flap, or by means of an adhesive tape which extends over the folded-down flaps and is secured on opposite sides of the bag walls.

To open a container or bag of the type herein disclosed, it is only necessary to break the adhesive agent which unites the various flaps and folds together, by substantially reversing the process or steps followed in bringing the end of the bag into the closed position.

25 Where a bag made entirely or partly of "cellophane" would have one or both ends thereof closed, in the manner which I have described, I intend to utilize the transparency of the "cellophane" by placing printed matter on one or both 30 sides of the member 7 at the ends thereof, whereby said printed matter will be visible through the "cellophane." My particular type of closure for the ends of the bag permits all of the printed or advertising matter referring to the contents of 35 the bag to be placed on the member 7 and does away with the necessity of printing on the "cellophane" out of which the bag may be formed. Of course, if the bag is made of non-transparent material, or other material other than "cello- 40 phane," then the bags may be printed or left plain in accordance with the whims of the user.

Particularly, however, with the use of "cellophane" bags, my system of closing the ends of the bags and placing the printed matter on the member 45 which is an essential part of the closed end of the bag, permits said bags to be developed into certain standardized sizes, and the use thereof for containing any number of varied commodities. Where the "cellophane" bag contains 50 printed matter referring to the contents thereof, then it is only possible to use that bag for one particular commodity. Thus my invention will permit a more general use of "cellophane" for bag purposes in that the manufacturer by reason 55 of quantity price production, will be able to reduce the cost thereof to the consumer, who in turn will benefit by the use of this material which is admirably adapted for merchandising processes.

60 It is contemplated by this invention that the outside of each of the flaps 5 and 6 of the non-transparent bags and the stiffener ends within the transparent bags, will be provided with printed or advertising matter thereon, whereby 65 either or both of the flaps may be placed in an upright position to indicate the contents, price, or

name of the material contained within the bag. I have also provided a perforation 10, through each of the flaps 5 and 6 adjacent the apex thereof to facilitate the mounting of said flaps on a rod or bar, and for thereby holding the same in a suspended or pendant position. The stiffener member in the end of the bag likewise assists in holding the bag in a position of set form, whereby the bag may be suspended in a hanging position by the supporting member extending through only 10 one of the upstanding flaps.

Having thus described this invention, what I claim and desire to secure by Letters Patent is:

1. A bag made of flexible, foldable material having closure flaps folded in overlapping relation and secured together to seal the top of the bag, said bag having a member formed of relatively stiff material arranged transversely thereon, provided with foldable opposite pointed ends thereon which extend within the closure flaps to 15 facilitate the movement of said closure flaps into overlapping relation.

2. In combination a bag made of flexible, foldable material and a relatively stiff member adapted to be placed in said bag on top of the 25 contents thereof, to assist in forming the closure for the top of said bag, said member having pointed projecting tabs on opposite ends thereof which parallel opposite sides of the bag, between which the remaining opposite sides of the bag are 30 adapted to be folded preliminarily to the final operation of folding down the first-mentioned sides of the bag and the tabs.

3. A bag made of flexible, foldable material having closure flaps folded in overlapping relation and secured together to seal the top of the bag, said bag having a cross member formed of relatively stiff material thereon provided with upstanding pointed tabs on opposite ends thereof which extend within and are foldable with opposite closure flaps, said member and tabs facilitating 40 the movement of all the closure flaps into overlapping relation.

4. A bag made of flexible, foldable material having closure flaps folded in overlapping relation 45 and secured together to seal the top of the bag, said bag having a member formed of relatively stiff material arranged transversely thereon, provided with foldable opposite pointed ends thereon which extend within the closure flaps to facilitate 50 the movement of said closure flaps into overlapping relation; and each of the outermost closure flaps and pointed ends having aligned perforations therethrough for supporting the bag in a suspended position.

5. A bag made of flexible, foldable material having closure flaps folded in overlapping relation and secured together to seal the top of the bag, said bag having a cross member thereon provided with upstanding tabs on opposite closure flaps, 60 said member and tabs facilitating the movement of all the closure flaps into overlapping relation and each of the outermost closure flaps and tabs having aligned perforations therethrough for supporting the bag in a suspended position.

JOHN M. DRIVER.
